UNITED STATES PATENT OFFICE.

RAYMOND L. RUOFF, OF PRESCOTT, ARIZONA.

AUTOMATIC BRAKE.

Application filed October 23, 1923. Serial No. 670,301.

To all whom it may concern:

Be it known that I, RAYMOND L. RUOFF, citizen of the United States, residing at Prescott, in the county of Yavapai and State of Arizona, have invented certain new and useful Improvements in Automatic Brakes, of which the following is a specification.

This invention relates to automatic brakes, and has particular reference to a device of 10 that kind, particularly adaptable for stopping the rotation of phonograph turn tables upon the completion of the playing of a record disposed upon the table.

The primary object of the invention is to 15 generally simplify and improve devices of the above kind whereby the same may meet with all of the requirements for a successful commercial use.

Another object of the invention is to provide 20 an automatic turn table stopping device for phonographs which will be thoroughly reliable and efficient in operation, and which will comprise a minimum number of parts of simple and durable form, 25 and so co-related as to render unlikely the probability of the device getting out of order.

A further object of the invention is to provide 30 a brake of the above kind depending upon its operation by relative displacement of parts caused by the sensation of movement of the tone arm of a phonograph.

Other objects will appear as the nature 35 of the invention is better understood, and the same consists in the novel form, combination, and arrangement of parts hereinafter more fully described, shown in the accompanying drawings, and claimed.

In the drawings, wherein like reference 40 characters indicate corresponding parts throughout the several views:

Figure 1 is a fragmentary view, partly in top plan and partly in horizontal section, of a phonograph equipped with a brake 45 mechanism constructed in accordance with the present invention.

Figure 2 is a view partly in elevation and partly in section of the device shown in Figure 1.

Figure 3 is a fragmentary side elevational view illustrating details of the brake release mechanism, and

Figure 4 is a fragmentary plan view showing further details of the device.

Referring more in detail to the drawings, 55 5 indicates the casing or cabinet of a phono-

graph which has the usual horizontal turn table 7 that is fixed upon the upper end of a vertical drive shaft 8 which is driven in the usual manner by a governor controlled spring 60 motor (not shown). It is to be understood that the record to be played is placed upon the turn table 7 in the usual manner for engagement by the needle 9 of a sound box 10 that is carried upon the inner end of a horizontally swinging tone arm 11, the outer end of which extends downwardly thru the top of the casing 5 and is hingedly mounted in the latter for permitting the swinging of the tone arm 11 as above mentioned. 70

A horizontally swinging brake lever 12 is suitably pivotally mounted upon the top of the casing 5 beneath the marginal portion of the turn table 7, and this lever carries a brake shoe 13 adapted to swing outwardly into engagement with the inner surface of the depending rim of the turntable 7 for stopping rotation of the latter in a well known manner. In accordance with the present invention a spring 14 is provided for automatically swinging the brake member 12 to braking position, or in such position as to engage the brake shoe 13 with the turntable. Pivotally mounted at one side of the turntable 7 for vertical swinging movement is a catch 85 15 that is normally urged downwardly by means of a spring 16 to engage behind the brake lever 12 for holding the latter in released position as shown in Figures 1 and 3, and one end of the catch 15 is directed upwardly in the form of a crank arm 17 to which is attached one end of a flexible operating element or wire 18.

An arm 19 has its outer end mounted upon the vertical portion of the tone arm 11, 95 so as to be capable of swinging horizontally and this arm extends inwardly between the top of the casing 5 and the turn table 7 where it is provided upon its free end with a friction gear segment 20. A stub shaft 21 is 100 provided on the top of the casing 5 beneath the turn table 7 and has a friction gear 22 journaled thereon, that has constant engagement with the friction gear segment 20, said friction gear 22 being fixed to a relatively 105 large worm gear 23 that meshes with a worm 24 secured upon a horizontal shaft 25 which is mounted in suitable bearings beneath the turn table 7. The shaft 25 is radially positioned as shown in Figure 1, and has a 110 bevelled gear 26 upon its inner end that is in turn meshed with a bevelled gear 27 fixed

upon the vertical shaft 8 of the turn table. The gearing thus described, constitutes means for causing swinging movement of the arm 19 in synchronism with the swinging movement of the tone arm 11 under the influence of the record to be played.

A second arm 28 is provided on the tone arm 11, and this arm has its outer end keyed as at 29 to the vertical portion of the tone arm whereby the arm 28 is caused to travel with the tone arm when the record is being played. The arm 28 is disposed directly above the arm 19 and in a plane directly below the turn table 7 and the inner end 15 of said arm 28 is pivotally engaged as at 30 with one arm of a bell crank lever 31 that is pivoted for horizontal swinging movement as at 32 upon the top of an intermediate enlarged portion 33 of the arm 19. The 20 other arm of the bell crank lever 31 is attached to the flexible element or wire 18, as at 34, and said wire 18 is extended through a suitable guide tube 35 that has its ends respectively attached as at 36 and 25 37 to the portion 33 of the arm 19 and the top of the casing 5 of the phonograph.

Movement of the arm 28 in one direction relative to the arm 19 is normally yieldingly prevented by means of a spring 38 that is 30 attached to the inner end of the arm 28 and to the enlarged portion 33 of the arm 19 as shown clearly in Figures 1 and 4. It is particularly noted that the arm 19 is not keyed to the tone arm 11 and may swing 35 relative to the latter.

In operation, the brake lever 12 is swung, so as to disengage its brake shoe 13 from the rim of the turntable 7 against the action of the spring 14, in which position said 40 brake lever is engaged behind the catch 15 for holding the brake shoe released, the catch 15 being shown in engaging position with respect to the lever 12 by means of the spring 16. As the needle 9 has been previously engaged with the starting point in 45 the groove of a record to be played, the release of the brake shoe 13 permits turning of the turntable 7 under the influence of its operating motor as is well known in the art. 50 When this takes place, the arm 28 is caused to swing with the tone arm 11 and through the gearing described, the arm 19 is also caused to swing in synchronism or unison with the tone arm and the arm 28. Thus, 55 during the playing of the record there is no relative displacement between the arms 28 and 19 and the brake will be held released. However, upon the needle 9 reaching the end of the sound groove in the record, 60 the swinging movement of the tone arm 11 ceases, and by reason of the connection of the arm 28 with said tone arm, said arm 28 is stopped. Continued rotation of the friction gear 22 causes the arm 19 to continue 65 to swing, so as to displace the same relative

to the arm 28 and thereby cause swinging of the bell crank lever 31 in a direction to cause a pull to be exerted upon the wire 18 for causing upward swinging movement of the catch 13 against the action of the springs 70 38 and 16. When this takes place, the catch is disengaged from the brake lever 12 and the spring 14 then immediately swings said lever 12 to engage its brake shoe 13 with the rim of the turntable for stopping the latter. The outer end of the lever 12 and the catch 15 are formed with finger pieces 75 for permitting their manual operation and there is sufficient length to the wire 18 and tooth 35 to permit the movement of the arms 19 and 28 as above mentioned.

From the above description, it is believed that the construction and operation, as well as the advantages of the present invention will be readily understood and appreciated 85 by those skilled in the art.

Minor changes may be made without departing from the spirit and scope of the invention as claimed.

What I claim as new is:

1. In an automatic turn table brake for phonographs, an arm adapted to be mounted to rotate relative to and upon the tone arm of the phonograph, a second arm having one end adapted for attachment to said tone arm to be caused to move therewith, means to cause travelling movement of the first named arm in unison with the tone arm and the second named arm and to cause movement of the first named arm past the stopping point of the tone arm at the completion of the playing of the record, and means operable upon such continued movement of the first named arm for arresting movement of the turn table.

2. In an automatic turn table brake for phonographs, an arm adapted to be mounted to rotate relative to and upon the tone arm of the phonograph, a second arm having one end adapted for attachment to said tone arm to be caused to move therewith, means to cause travelling movement of the first named arm in unison with the tone arm and the second named arm and to cause movement of the first named arm past the stopping point of the tone arm at the completion of the playing of the record, means operable upon such continued movement of the first named arm for arresting movement of the turn table, said last named means comprising a normally applied brake member, a latch for holding the brake member released, and means for releasing said latch operatively associated with the first named arm.

3. In combination with the horizontally swinging tone arm of a phonograph and the rotatable turntable of the latter, an arm having its outer end rotatably disposed upon the tone arm and its inner end disposed be-

neath the turntable, gearing between the turntable and the inner end of said arm for causing the latter to swing in unison with the tone arm during the playing operation and to travel after movement of the tone arm has ceased upon completion of the playing operation, a second arm keyed to the tone arm to swing therewith, a bell crank lever pivoted upon the first named arm and having one end pivotally engaged with the inner end of the second named arm, a normally applied brake, a latch for holding said brake released, and means connecting said latch with said bell crank lever for releasing the catch upon cessation of movement of the second named arm and continued movement of the first named arm.

4. In combination with the horizontal turntable and the horizontally swinging tone arm of a phonograph, an arm having

its inner end disposed beneath the turntable and having its outer end mounted upon the tone arm whereby said arm may swing horizontally relative to the tone arm, driving connection between the turntable and the inner end of said arm including friction gearing for swinging said arm in unison with the tone arm when the latter is moved during the record playing operation, a second arm having its outer end keyed to the tone arm to move therewith, and means operatively connected to said arm and operable upon relative displacement of the arms due to continued swinging movement of the first named arm when the tone arm and second named arm are stopped at the end of a record, for releasing a normally applied brake of the turn table.

In testimony whereof I affix my signature.

RAYMOND L. RUOFF.
